(57) **CLAIM**

The ornamental design for an aircraft docking station, as shown and described.

DESCRIPTION

FIG. 1 is a front perspective view of an aircraft docking station showing my new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines in the figures show portions of the aircraft docking station which form no part of the claimed design. The shade lines show surface contour and not surface ornamentation.
